(57) **CLAIM**

The ornamental design for a ball mount, as shown and described.

DESCRIPTION

FIG. 1 is a front view of a ball mount.

FIG. 2 is a rear view of the ball mount.

FIG. 3 is a first side view of the ball mount.

FIG. 4 is a second side view of the ball mount.

FIG. 5 is an overhead view of the ball mount; and,

FIG. 6 is a bottom view of the ball mount.

The broken line showing of portions of the design is included for the purpose of illustrating the environment and forms no part of the claimed design.
